UNITED STATES PATENT OFFICE.

LOUIS LOISELLE, OF VALLEYFIELD, QUEBEC, CANADA.

REFRIGERATOR.

SPECIFICATION forming part of Letters Patent No. 225,992, dated March 30, 1880.

Application filed September 22, 1879.

To all whom it may concern:

Be it known that I, LOUIS LOISELLE, of Valleyfield, in the county of Beauharnois and Province of Quebec, Canada, have invented 5 certain new and useful Improvements in Refrigerators; and I declare the following to be a description of my said invention, sufficiently full, clear, and exact to enable others skilled in the art to which it appertains to make and 10 use the same, reference being had to the accompanying drawings, which form a part of this specification, and in which—

Figure 1 represents a part front part vertical sectional view of a refrigerator embracing 15 the features of my invention. Fig. 2 is a transverse vertical section of the same at line X X. Fig. 3 is a horizontal sectional view, one-half at the height of line Y and the other half at line Z; and Fig. 4 is a view of one of the 20 drawers.

The nature of my invention relates to the peculiar construction and arrangement of a refrigerator with a view to effecting a saving 25 of ice, obtaining a better circulation of fresh air inside, and keeping articles stored in it in a perfect condition.

In the drawings, A denotes the bottom or floor; B, the back, and C the sides, all of 30 which are made with an outside and inside casing, a b, between which is a space, c, for air, or, if preferred, containing a filling of any suitable porous non-conducting material.

D D indicate the doors, which I form in two wings set at right angles, or nearly so, rigidly 35 secured to each other, and connected by hinges d d to the side pieces, C', so as to swing in the manner indicated, the inner wing, D', being of such size as to just pass through the space or door-opening, so as to swing outward or inward, as desired. If desired, the doors may 40 be hung by pivots at the junction or angle of the wings, projecting into the lintel and sill at the top and bottom of the door. The edges of the doors are rabbeted, so as to form close 45 joints with the surrounding portions, and they are formed of inside and outside casings, with spaces or non-conducting filling similar to the bottom, back, and sides.

Pins f or other suitable stops are placed in 50 the jambs of the doors, which prevent the inner wing, D', from swinging outward farther

than flush with the front of the refrigerator (see Fig. 3) when in ordinary use; but by removing said pins f the door can be swung outward, as indicated by dotted lines.

55

Secured to the interior sides of the wings D' D' of the door are shelves E. These shelves are formed of wire or of solid material having perforations through them, the object being to insure a free circulation of cold air around 60 the articles placed thereon.

When the outer wing of the door is opened the inner wing, D', will be closed, so that the cold air is prevented from escaping from the interior of the refrigerator while the operation 65 of loading or unloading the shelves E is going on. By this means a large saving of ice is effected.

F F indicate drawers, which afford additional space in which to store provision, meat, 70 vegetables, or other articles. In the sides of the drawers are formed openings e, to allow free circulation of cold air through them, and space is left around the drawers for the same purpose. A portion of the drawers at their inner 75 ends are covered by plates F', or thin horizontal partitions having their front edges turned upward. These serve as guards when the drawers are pulled out, and close the openings, so that the cold air from the interior will 80 not escape while the drawers are open.

G indicates a stand of shelves arranged in the central rear part of the chamber, which may be used for supporting articles that do not require to be often taken out, as access 85 thereto is had only by opening outward inner leaf, D', of the door D.

I indicates the ice-box, formed partly by the sides i and bottom j, extending from the front to back of the refrigerator, and located in the 90 upper central part of the chamber. Sufficient space is left between the upper edges of the sides i and lid J, or cover, of the refrigerator for the passage of currents of air, so that warmer currents rising to the upper part of 95 the chamber will be continually drawn over the ice by condensation, and therefore the continual sinking to the lower part of the chamber of the air immediately surrounding the ice. Thus a constant circulation of air is kept up. 100

K indicates a reservoir formed in the front portion of the ice-box I, and used for drinking-

water, said water being kept cool by its close proximity to the ice in the box I. Said reservoir K is provided with a suitable cover to shut out the odors of the various articles of food, and a cock, L, projects at the front of the casing, by means of which the water can be drawn from the reservoir K as it is desired for use.

The cover or lid J has in it a chamber, m, which communicates with the inside of the refrigerator-chamber through the ventilating-holes m', and with the exterior through the two air-passages n n, near the rear corners of the lid.

15 Within the sides C are placed the perforated ventilators M, extending from front to rear, and located between the outer and inner casings, a b, and surrounded by the non-conducting material, when such is used.

20 These ventilators M communicate with the outside air through the pipes M', which open at the upper rear edge of the back B.

The inner casing of the back B is made somewhat shorter than the outside casing, thus 25 leaving an opening, O, through which the air of the ice-chest I may be continually exchanging for the air circulating through the space between the outer and inner casings, a b, of the bottom A, back B, and side C.

30 As a result of this system of ventilation of the inclosed space or non-conducting material therein, the surfaces of the refrigerator are kept dry and all sweating is prevented.

P is a drip-pipe extending from the ice-box

I down to and through the bottom A, and is 35 for leading off the waste-water from the ice-box. This pipe is carried down below the bottom A, and on its end is fitted the water-dish R, having a central pipe or thimble, s, that fits sufficiently tight over the end of the drip-pipe 40 P to support the water-dish. The pipe P has its vent near the bottom of the dish R, so that the water will flow from the pipe into the dish.

It is obvious that the lower end of the pipe P or central tube s, being surrounded by water, 45 will prevent the warm air of the room from passing into the refrigerator through the drip-pipe P.

Having thus described my invention, what I claim therein, and desire to secure by Letters 50 Patent, is—

1. The perforated ventilating-pipes M, arranged as described, in combination with the air-pipes M', disposed within the air-space e, as shown, and for the purpose described. 55

2. The hinged cover J, provided with the chamber m, having centrally-ventilating holes m', in combination with the chest provided with air-space e, ventilating-pipes M, and air-pipes M', substantially as and for the purpose 60 set forth.

Witness my hand this 11th day of September, A. D. 1879.

LOUIS LOISELLE.
